UNITED STATES PATENT OFFICE.

EPHRAIM N. RITTASE, OF BALTIMORE, MARYLAND.

CIGAR-HOLDER.

1,308,113.

Specification of Letters Patent.

Patented July 1, 1919.

Application filed May 22, 1918. Serial No. 236,002.

To all whom it may concern:

Be it known that I, EPHRAM N. RITTASE,
a citizen of the United States, residing at
Baltimore, in the State of Maryland, have in-
5 vented a new and useful Cigar-Holder, of
which the following is a specification.

The subject of the present invention is a cigar holder in which the end of a cigar may be secured while being smoked.

10 The main object of the invention is the provision of means for gripping the ends of cigars of different shapes.

Another object of the invention is the provision of a cigar holder which will not leak air between the holder and the cigar.

The invention also contemplates the provision of a cigar holder with a solid mouthpiece and cigar engaging means conformable to the shape of a cigar.

20 Another object of the invention is the provision of a holder having the advantages of the present soft rubber holder but avoiding the disagreeable taste due to the soft rubber.

The invention also contemplates generally improving the construction and enhancing the utility of cigar holders.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without

33 within the scope of what is claimed without departing from the spirit of the invention.

A practical embodiment of the invention is shown in the accompanying drawing, wherein:—

40 Figure 1 is a view in side elevation of a cigar holder constructed in accordance with the invention;

Fig. 2 is an enlarged view in central longitudinal section of the same;

45 Fig. 3 is a cross section on the line 3-3 of Fig. 2.

Referring to the drawing by numerals of reference:—

In carrying out the invention there is provided a mouth piece 1, formed of any suitable solid, non-yielding substance, and through which the usual air duct is formed. An exteriorly threaded nipple 2 is formed

on the forward end of the mouth piece 1, and this nipple is threaded into the rear end 55 of the cigar engaging portion 3.

The cigar engaging portion 3 is apertured to receive the end of a cigar and to permit the passage therethrough of the smoke, and is preferably formed of resilient material, such as rubber, which will conform to various sizes and shapes of cigars and which will tightly grip the cigar. The portion 3 of the holder is preferably formed with an annular enlarged portion, or reinforcing band 4, which tends to strengthen the cigar engaging portion at the point of connection with the mouth piece. The forward end of the cigar engaging portion 3 is preferably formed with an annular beading 5 which adds to the strength of the end and assures a firm grip of the portion about the cigar.

To protect the cigar engaging portion 3 from injury, due to the heat from the ignited cigar when the cigar has burned to the end, the portion 3 of the holder is lined with strips of heat insulating material 6, which strips are preferably arranged circumferentially of the portion 3, of which each strip 80 extends longitudinally. Each strip is secured along one longitudinal edge to the inner wall of the portion 3, while its other edge overlaps the adjoining secured edge of the next strip. This will allow the portion 3 to expand and contract to accommodate larger or smaller cigars. 85

Having described the invention, what is claimed as new and sought by Letters Patent, is:—

A cigar holder including a non-yielding mouth piece, a resilient cigar holding element, strips of heat insulating material arranged within and circumferentially of the cigar holding element, each strip being secured to the resilient cigar holding element, along one longitudinal edge thereof, the opposite edge of each strip overlapping the secured edge of the adjacent strip. 95

In testimony that I claim the foregoing 100 as my own, I have hereto affixed my signature in the presence of two witnesses.

EPHRAIM N. RITTASE.
